US00D979108S

(12) **United States Design Patent** (10) **Patent No.:** **US D979,108 S**
Hammerbeck (45) **Date of Patent:** **** Feb. 21, 2023**

(54) **VEHICLE HEADLIGHT**

(71) Applicant: **Polestar Performance AB**, Gothenburg (SE)

(72) Inventor: **Malte Hammerbeck**, Torslanda (SE)

(73) Assignee: **Polestar Performance AB**, Gothenburg (SE)

(**) Term: **15 Years**

(21) Appl. No.: **29/746,644**

(22) Filed: **Aug. 14, 2020**

(30) **Foreign Application Priority Data**

Feb. 14, 2020 (EM) 007695242-0003

(51) **LOC (14) Cl.** **26-06**

(52) **U.S. Cl.**
USPC **D26/28**

(58) **Field of Classification Search**

USPC 362/42, 507, 496, 460; D26/122, 123, D26/36, 39, 34, 35

CPC F21S 43/237; F21S 43/15; F21S 43/00; F21S 41/32; F21S 41/36; F21S 41/50; F21S 41/26; F21S 41/00; F21V 21/04

(57) **CLAIM**

I claim the ornamental design for a vehicle headlight, as shown.

DESCRIPTION

FIG. 1 is a front left perspective view of a vehicle headlight. FIG. 2 is a front right perspective view of the vehicle headlight depicted in FIG. 1.

FIG. 3 is a front view of the vehicle headlight depicted in FIG. 1.

FIG. 4 is a right side view of the vehicle headlight depicted in FIG. 1.

FIG. 5 is a top view of the vehicle headlight depicted in FIG. 1.

FIG. 6 is a left side view of the vehicle headlight depicted in FIG. 1.

FIG. 7 is a bottom view of the vehicle headlight depicted in FIG. 1; and,

FIG. 8 is a rear view of the vehicle headlight depicted in FIG. 1.

1 Claim, 8 Drawing Sheets
